MICROMETER CALIPER

Arthur Brown, Cranston, R. I.

Application November 14, 1935, Serial No. 49,797

15 Claims. (Cl. 33—164)

My invention relates to a micrometer caliper and more particularly to an auxiliary mechanism attached to or integral with the usual micrometer frame.

5 An object of my invention is to combine in a single device means for performing the functions of both a micrometer caliper, and that of a limit gage, the latter purposed to assist in determining finished size.

10 Additional objects are to enable the number of thousandths, ten thousandths, or other finer graduations to be automatically measured, and to enable all micrometric measurements to be ascertained by the sense of feeling exclusively, and 15 without the necessity of dials, dial graduations, or other marking, thus insuring both speed of operation and extending the field of use of micrometer calipers.

Further objects are to attain the above results in a structure facile to assemble and disassemble, and inexpensive to construct.

Other objects and advantages will herein be adverted to and be apparent to those skilled in the art.

25 To the above ends primarily my invention consists in such novel parts and combinations thereof as fall within the scope of the appended claims.

In the accompanying drawings which are a part of this specification, and in which is shown 30 merely a preferred form of embodiment of my invention,

Figures 1, 2, and 3 are a side elevation, a top plan view, and a rear end elevation respectively of my novel device,

35 Figure 4, an enlarged fragmentary plan view of the same with the clamping retaining nut of the stop disk removed,

Figure 5, a plan view similar to that of Figure 4 showing the operating parts in a second position,

40 Figure 6, a top plan view of the handle detached,

Figure 7, a bottom plan view of the operating member, and

Figure 8, a side elevation of my micrometer 45 partially in section taken on line 8—8 of Figure 2.

In the drawings 8 is the thimble, 9 the barrel, 10 the screw or spindle, and 11 the frame, inclusive of the anvil portion 12 of the frame, of a common type of micrometer caliper of any usual or preferred construction provided with the usual barrel scale 13 and thimble scale 14.

50 A handle 17 is formed with a body portion 18 and a forwardly extending lug portion 19 provided with a vertical longitudinally extending slot 55 20 forming resilient clamping sections or ears

21 internally recessed, as at 22, to receive a portion of the frame 11 to which the ears are securely clamped by screws 24 passing transversely through the sections. The handle 17 may be formed integrally with the frame 11 if preferred.

The body of the handle is provided with a finger hole 26 for admitting the index finger of the operator to grasp the device. Above the hole is a vertical bore 27 to loosely receive the shank 28 of an actuating member 29, whose head 30 includes an upper lateral tapering portion 31 provided in this instance with a series of index numerals 32, ten in number, while the lower lateral portion of the head is peripherally milled as at 34. The bottom of the head is flat and is provided with an annular series of equally inter-spaced cavities 36, in this case ten in number, adapted when the member 29 is manually turned by the operator's thumb, to successively register with a detent or pawl 38 consisting of a ball 39 supported by a helical spring 40 in a vertical recess 41 in the upper portion of the handle.

Fixed to or integral with the head of the operating member 29 is a pinion 42 meshing with peripheral teeth 43 upon a segmental arm 44 pivoted to the barrel 9 through an opening 46 in the end of the arm opposite the teeth. The arm 44 slidably rests upon a vertical extension or lug 48 on the body of the handle, and is provided with a transversely disposed arcuate slot 49. There are upturned lateral lugs 50 upon the segmental arm 44 adjacent the ends of the slot 49. Through the slot loosely passes a stud 51 whose lower end 52 is threaded in an opening 54 in the lug 48 and whose threaded upper end 55 carries a check nut 57 adapted to engage the upper face of a stop disk 58 supported by a flange 59 upon an intermediate portion of the stud, and having a central opening 60 to loosely receive the stud. By tightening the nut 57 the disk 58 is clamped to the flange 59 in any desired position of circular adjustment.

In detail the disk 58 includes two oppositely offset segmental portions 62, each comprising a series 64, in this case of five, stepped peripheral contact faces 65 having ten thousandths indicated by the index numerals 2, 4, 6, 8, and 10. Each step 66 of each series decreases successively in depth from the outermost to the innermost end of its segmental portion, said depth being such as to cause the difference in movement of the arm 44 allowed by the adjacent face 65 to correspond to an adjustment of the spindle 10 one ten thousandth of an inch. The presence of the 55

said index numerals while convenient is not imperative.

Fixed to the segmental arm or lever 44 intermediate the slot 69 and its pivoted end, and midway its width, is an upright post 68 provided with a transversely curved longitudinal slot 69.

Fixed by friction to the thimble 8 of the micrometer, or integral therewith, is a collar 71 provided at its lower end with a peripheral flange 72, and at its upper end, with an external thread 73 adapted to engage an internal thread 74 upon a clamping nut 75 adapted to bear against a sleeve 77. Integral with the sleeve is a resilient or yieldable radial arm or finger 78 having its free end slidably registering in the slot 69, as well as slightly transversely curved.

In setting my device, the nut 75 is loosened and the thimble is by the operator's thumb and finger rotated the desired extent to enable, by the co-operation of the barrel scale and thimble scale, the determination of the thousandths of an inch sought. The setting is continued by seeking the residual measurement in ten thousandths of an inch, which operation is effected by rotating with the thumb the actuating member 29 from its zero position a distance equal to the number of ten thousandths required either in excess of or less than the thousandths already ascertained from the barrel and thimble graduations, the direction of movement of the actuating member being dependent upon the operator's purpose of effecting either an increase or a diminution of the desired graduations.

The manipulation of the actuating member 29 in this setting operation did not move the thimble because of the loosened condition of the nut 75. Now, however, the nut is manually tightened to clamp the member 77 into rigid relation with the thimble and post 68, and the setting operation is then continued by returning the actuating member to its zero position, whereby the thimble is rotated to advance or retract the spindle 10 the number of ten thousandths required to bring the spindle to a final position. In effecting the described rotation of the thimble the circular movement of the actuating member 29 imparted through the toothed member 42, a transverse movement to the arm 44, which through the post 68 and arm 78 imparted the necessary impulse to the latter.

The stop disk 58, during the above described setting operation was either entirely removed, or was adjusted to the position shown in Figure 4, wherein the deepest contact faces of the stop disk, namely those adjacent the index numerals 10, were opposite the stop lugs 50 so as to insure an unimpeded maximum swing of the arm 44 of at least ten ten-thousandths of an inch.

During the above manual turn or swing of the actuating member 29 to its zero position the operator was enabled to count the number of ten-thousandths of an inch covered by the swing instantly and solely by the sense of feeling. This was effected by counting the number of impacts of the detent 33 in the successive cavities 36. The series of index numerals 32 while a convenience, are not necessary.

The presence of the vertical groove 69 in post 68 enables the finger 78 to slide loosely therein during the ascent or descent of the thimble during the setting operation, and facilitates disengagement of the finger from the post when or if disassembly of the parts of my device is desired.

By virtue of the resiliency of the finger 78, and

of the transverse curvature of the groove 69 and of the finger 78 it is possible, by manually turning the thimble 8 with the nut 75 tightened, to swing the finger laterally out of engagement with the post 68 whereby coarse adjustments may be made without disturbing the setting.

While the graduations 13 and 14 on the barrel and thimble, and the numerals on actuating member 29 are a convenience, they are not indispensable as my device can be set to any predetermined dimension without their use. This feature is of value particularly to persons with faulty vision. My device is set without the aid of the graduations or numerals as follows.

With the finger 78 engaging the groove 69 in post 68, nut 75 is loosened and the thimble turned until the end of spindle 10 comes in contact with anvil 42, the setting then being zero. Nut 75 is then tightened and the thimble turned in the opposite direction, in which operation the finger 78 becomes disengaged from post 68 and encounters post 68 at each revolution of the thimble. Through the medium of the successive contacts of finger 78 with the post 68 the number of revolutions of the thimble is felt and counted by the operator. The total axial movement of the spindle 10 is thus known from the number of revolutions of the thimble and the pitch or lead of the micrometer caliper screw which is in this instance twenty-five thousandths.

The residual number of thousandths in the predetermined dimension, if any, are obtained by means of actuating member 29. Nut 75 is loosened and disk 58 either entirely removed or is adjusted to permit a full revolution of actuating member 29 as shown in Figure 4. Member 29 is next rotated in a counter-clockwise direction, as viewed from the top, and until one lug 50 comes in contact with disk 58, if the latter is present, or, if absent, with the stud flange 59 whose diameter is equal to the minimum diameter of the member 62. This rotation of actuating member 29 did not move the thimble because of the loosened condition of nut 75. Now, however, nut 75 is manually tightened and actuating member 29 rotated in the opposite direction until the opposite lug 50 comes in contact with disk 58 which operation rotates the actuating member one revolution and the thimble one twenty-fifth of a revolution corresponding to an axial movement of spindle 10 of one thousandth of an inch. This operation of nut 75 and actuating member 29 is repeated until spindle 10 has been adjusted the residual number of thousandths.

The residual number of ten thousandths in the predetermined dimension, if any, are obtained by loosening nut 75 and rotating actuating member 29, again in a counter-clockwise direction, to a central position as in Figure 4. This is done by counting the number of cavities 36 encountered by detent 33 until one half the total number of cavities 36 have been encountered, in this case five. This rotation of actuating member 29 is then continued until an additional number of cavities 36 have been encountered corresponding to the residual number of ten thousandths required. Nut 75 is now tightened and pin 29 rotated in a clockwise direction until the same number of cavities have been encountered, thus bringing actuating member 29 back to the central position and completing the setting, all without the use of the operator's eyes.

When it is desired to employ my device to perform the function of a limit gage the setting is 75

as follows after the above described steps of finding in ten thousandths the mean dimension of the work have been taken. The nut 57 is first loosened and the disk 58 manually turned to bring the particular contact faces of the stop disk indicating the maximum limits or allowance, measured in ten thousandths, into the path of the stop lugs 59, and the nut 57 tightened. In Figure 5 the contact faces adjacent the index numerals 4 are shown so positioned, the maximum limit or allowance in this instance being four ten thousandths of an inch. The operation of the set parts is effected by turning the actuating member 29 from its position shown in Figure 4 to its position shown in Figure 5 thereby bringing one of the lugs 59 against one of the two contact faces adjacent one index numeral 4, thus indicating the number of ten thousandths of an inch added to the ten thousandths already obtained from the original setting. In this instance the counting of the impacts of the detent upon the actuating member is unnecessary.

Those skilled in the art will readily realize that the particular mechanism herein shown may be variously changed and modified without departing from the spirit of my invention or sacrificing the advantages thereof, and that the disclosures herein are illustrative only, and my invention is not limited thereto.

30 I claim:—

1. In a micrometer caliper, the combination with the thimble, barrel, spindle and frame, of a handle upon the frame, an actuating member rotatably mounted in the handle, teeth upon the member, an arm pivotally engaging the barrel at one end, segmentally disposed teeth upon the other end of the arm engaging the first teeth, and means operatively connecting the thimble with the arm whereby movement of the actuating means produces a corresponding movement of the thimble.

2. In a micrometer caliper, the combination with the thimble, barrel, spindle and frame, of a handle upon the frame, an actuating member 45 rotatably mounted in the handle, teeth upon the member, an arm pivotally engaging the barrel at one end, segmentally disposed teeth upon the other end of the arm engaging the first teeth, and means for selectively connecting and disconnecting the thimble with the arm for simultaneous actuation.

3. In a micrometer caliper, the combination with the thimble, barrel, spindle and frame, of a handle upon the frame, a laterally movable arm pivotally secured to the barrel, a post upon the arm, a resilient finger mounted on the thimble engaging the post, and rotary means on the handle engaging the arm for actuating the arm.

4. In a micrometer caliper, the combination with the thimble, barrel, spindle and frame, of a handle upon the frame, a detent in the handle, an actuating member pivotally mounted in the handle adjacent the detent provided with a plurality of curvilinearly arranged cavities adapted to successively receive the detent, peripheral teeth upon the member, a movable arm pivotally supported at one end by the barrel, a curved series of teeth upon the other end of the arm meshing with the first teeth, and means for connecting the arm with the thimble.

5. In a micrometer caliper, the combination with the thimble, barrel, spindle and frame, of a handle upon the frame, an actuating member rotatably mounted upon the handle provided with peripheral teeth, an arm pivotally engaging the

barrel and provided with peripheral teeth meshing with the first teeth, a post upon the arm, a collar fast to the thimble provided at its upper end with an external thread, a lateral flange upon the lower end of the collar, a sleeve loose on the collar and supported by the flange, a lateral finger upon the sleeve engaging the post, and a clamping nut resting upon the sleeve and provided with a thread engaging the first thread.

6. In a micrometer caliper, the combination with the thimble, barrel, spindle and frame, of a handle upon the frame, a segmental arm pivotally attached at one end to the barrel and provided intermediate its length with a transverse slot, lateral lugs upon the arm, teeth upon the free end of the arm, a stud upon the handle projecting loosely through the slot, a stop disk upon the stud above the arm in the path of the lugs, a nut upon the stud engageable with the disk, an actuating member loosely mounted in the handle 20 and provided with peripheral teeth meshing with the first teeth, and operative connections between the arm and the thimble.

7. In a micrometer caliper, the combination with the thimble, barrel, spindle and frame, of a handle upon the frame, a segmental arm pivotally attached at one end to the barrel and provided intermediate its length with a transverse slot, lateral lugs upon the arm, means for connecting the arm to the thimble, a stud upon the 25 body projecting loosely through the slot, a radially adjustable stop disk upon the stud, a plurality of peripheral contact faces disposed in stepped relation to each other upon the disk in the plane of the lugs, and rotatable means upon the handle 30 for swinging the arm.

8. In a micrometer caliper, the combination with the thimble, barrel, spindle and frame, of a handle upon the frame, a segmental arm pivotally attached at one end to the barrel and provided intermediate its length with a transverse slot, lateral lugs upon the arm, means for connecting the arm to the thimble, a stud upon the body projecting loosely through the slot, a radially adjustable stop disk upon the stud in the 45 plane of the lugs comprising two oppositely offset segmental portions, and rotatable means upon the handle for swinging the arm.

9. In a micrometer caliper, the combination with the thimble, barrel, spindle and frame, of a handle upon the frame, a segmental arm pivotally attached at one end to the barrel and provided intermediate its length with a transverse slot, lateral lugs upon the arm, teeth upon the unpivoted end of the arm, means for connecting 55 the arm to the thimble, a stud upon the body projecting loosely through the slot, a radially adjustable stop disk upon the stud in the plane of the lugs comprising two oppositely offset segmental portions, each provided with stepped peripheral contact faces, a detent in the handle, an actuating member pivotally mounted in the handle provided with cavities adapted to successively receive the detent when the member is rotated, and peripheral teeth upon the member engaging 60 the first teeth.

10. In a micrometer caliper, the combination with the thimble, barrel, spindle and frame, of a handle comprising an upwardly extending body, and horizontal clamping ears embracing the 70 frame, clamping screws in the ears, said body being provided in its lower portion with a finger opening, and in its upper portion with a vertical bore, a vertical extension upon the top of the body portion adjacent the bore, an actuating 75

- member comprising a shank loose in the bore and a head resting on the body including a pinion fixed to the head, a segmental arm pivotally attached at one end to the barrel and resting upon the extension, peripheral teeth upon its other end meshing with the pinion, and operative connections between the arm and the thimble for rotating the thimble in response to movement of the arm.
5. 11. In a micrometer caliper, the combination with the thimble, barrel, spindle and frame, of a handle upon the frame, an arm pivotally engaging the barrel at one end, manually movable means upon the frame for moving the arm, and means for detachably connecting the thimble to the arm.
10. 12. In a micrometer caliper, a body comprising a frame, a handle and a barrel, a segmental arm pivotally supported on said body, and provided with a transverse slot and with peripheral teeth, lateral lugs upon the arm, a stud upon the body projecting loosely through the slot, a stop disk upon the stud in the plane of the lugs, and an actuating member loosely mounted in the handle and provided with teeth engaging the first teeth.
15. 13. In a micrometer caliper, a body comprising a frame, a barrel, and a thimble, and adjustment means comprising a lever pivoted on said body, an actuating member mounted on said body and operatively connected to said lever, means for limiting movement of the lever to a predetermined distance, and means operatively connecting said lever to said thimble to rotate said thimble on movement of said actuating member.
14. In a micrometer caliper, a body comprising a frame, a barrel, and a thimble, and adjustment means comprising a lever pivoted on said body, an actuating member mounted on said body and operatively connected to said lever, means for limiting movement of the lever to a predetermined distance, said means including an adjustable stop element, and means operatively connecting said lever to said thimble to rotate said thimble on movement of said actuating member.
15. 15. In a micrometer caliper, the combination with the thimble, barrel, spindle and frame, of a handle upon the frame, a laterally movable arm pivotally secured at one end to said barrel, a post upon the arm provided with a longitudinal slot, a resilient finger supported by the thimble slidably engaging the post in the slot, and rotary means carried by the handle and engaging the other end of the arm for actuating the arm.

ARTHUR BROWN.
